Primary Examiner — Barbara Fox*Assistant Examiner* — Chelsea Sealey(74) *Attorney, Agent, or Firm* — Nixon Peabody LLP;
Jeffrey L. Costellia(57) **CLAIM**

I claim, the ornamental design for a portable information terminal, as shown and described.

DESCRIPTION

FIG. 1 is a front view of a portable information terminal showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a bottom right side perspective view thereof.

The portable information terminal can function as a computer, a media reproducing device (e.g., a music player, a movie player, or a game player), a media storage device, a communication device (e.g., a mobile phone), or the like, for example. The portable information terminal can be worn or carried on arms, legs, etc. The portable information terminal includes a convex curved display on one surface of a housing thereof.
